AWNNG ATTACHMENT

Application filed July 16, 1928. Serial No. 293,075.

This invention relates to improvements in awnings or curtains for windows, and particularly relates to a device as an attachment which can be applied to automobile windows 5 to provide a curtain awning therefor.

Objects of the invention are to provide a device which can be applied as an attachment to any window; to provide such a device which is operative by the curtain spring alone; to 10 provide an improved pawl and ratchet mechanism including a tubular arm having a pawl 15 slidable therein, along with means for detachably securing the pawl within the arm for limited movement and providing a simple 20 and cheap construction wherein no springs are used; to provide an improved arm for the purpose set forth formed from a single piece 25 of sheet metal and rolled; to provide a bushing which acts as a stop in conjunction with a detachable stop carried by a pawl rod which traverses the bushing, to limit withdrawal of the rod; and to arrange the parts so that the stop is maintained in operative relation after placement, and after the parts have been 30 adjusted to operative position.

Features of the invention also include all details of construction, as well as combinations and sub-combinations of the parts.

Objects, advantages and features of the invention will appear in the description of the drawings forming a part of this application, and in said drawings.

Figure 1 is a face view of a window equipped with one form of the present device, to illustrate the principles of the invention;

Figure 2 is a vertical longitudinal section on line 2—2 of Figure 1 looking in the direction of the arrow;

Figure 3 is a detailed section illustrating the connection of the pawl with the pawl arm and ratchet;

Figure 4 is a detail sectional view, the parts positionally corresponding to those shown in Figure 2; and

Figure 5 is an end view of the pawl arm.

A frame having an opening therein is generally designated at 1. This may be the window of an automobile. Attached on each of the opposite vertical faces 2 of the opening is 50 a plate 3 suitably secured as by screws 4 pass-

ing through longitudinally disposed slots 5. Two of these slots are used but only one is shown in Figure 3. Each one of the plates 3 has a cylindrical boss 53, the periphery of which is provided with ratchet teeth 6 extending in direction of the axis of the cylinder, said ratchet teeth, in this instance, only extending through an arc of about 180° and the teeth being faced in a direction outwardly from the window opening.

A curtain roller is indicated at 10 and rotatably stepped in the plates 3, and has thereon a curtain 11. This roller may be of any approved construction including a spring, but is not provided with the usual ratchet mechanism.

An arm is provided for each boss 53 and is pivoted to swing about the boss axis. Each arm comprises a tubular portion 12 and a flat portion 13. The tubular portion 12 is open at that side which faces the plates 3 to provide a longitudinal slot 15 and also to permit the tubular element to be brought as closely as possible to the plate as best shown in Figure 5, thus making for compactness. This slot extends the full length of the tube 12. The tube 12 is enlarged as at 20 adjacent the ratchet, thus providing tube portions each of a different diameter, merging into one another. This arrangement constitutes an important feature of the invention. The enlarged tubular portion 20, as best shown in Figure 2, merges into the flat portion 13, and the slot 15 is co-extensive with this enlarged tubular portion. The two portions 12 and 20

provide interior diameters one greater than the other. Within the tubular portion 12 is inserted and snugly fitted a bushing 25, and the tube 12 has an inturned portion 26 as a stop to prevent outward movement of the bushing. The inner end 28 of the tube projects beyond the merging point 30 of the tube 12 with the tube 20, in a direction toward the ratchet teeth, as clearly shown in Figure 4 and this is a feature of the invention.

Secured to the bottom of the curtain is a frame having bent portions 35 which are formed to act as pawls. In fact the curtain may be considered as being connected to a pawl and to be capable of controlling and of

being controlled by the pawl. Each of these pawls slides within a respective bushing 25, terminal 36 being engageable with any tooth 6.

Referring to Figure 4, it will be seen that the outward movement of the pawl 35 under entraining action of the curtain, actuated by the spring of the curtain, is prevented by a cross-pin 40 which passes loosely through an opening 41 of the arm. By inspection of Figure 2 it will be seen that the roller spring acts on the curtain 11 in a manner to translate the pawls in direction of the arrow *a*, when the parts are positioned as shown in full lines in Figure 2. In this full line position, the pins 40 limit the outward movement of the pawls 35 by engaging against the projecting inner ends 28 of the bushings 25 as stops, see Figure 4, the parts of which positionally correspond to those of Figure 2. In this position the pawls are free of the teeth 6.

A feature of the invention includes the arrangement of the pin in relation to the end of the bushing 25 and to the enlarged tubular portion 20, and point of emergence between this portion and the portion 12. In assembling the device the bushing 12 is passed over a pawl arm 35 and then rotated to bring the opening 41 in opposition to the slot 15, and the pin 40 is then dropped into the opening 41. After introduction of the pin 40 the element 12 is turned, in this instance, through an angle of 90° so that, as shown in Figure 4, the pin cannot thereafter be disengaged. It will be noted that the length of the pin is less than the inner diameter of the tubular portion 20, so that slight play is allowed. It will again be noted that the tube 25 projects beyond the point of emergence 20 of the tube 12 with enlarged tubular portion 20 so that there is no possibility of the ends of the pin engaging against the walls at point of emergence, to jam. The pin has a limited linear movement. In disassembling, the element 12 is merely turned to a position in which the pin is free to fall through the slot 15. As shown in dot-and-dash lines in Figure 4, the movement of the pin 40 toward the ratchet teeth 6 is not sufficient to allow it to be disengaged from the enlarged tubular portion 20, that is is not sufficient to allow it to travel outwardly beyond this enlarged tubular portion, in a direction toward the teeth.

By the use of this invention, no spring is required, the device is simple, cheap and is easy to assemble. It will be understood that after the introduction of the pin and after turning of the element 12 or of the rod so that the pin occupies a position shown in Figures 3 and 4, a headed pivot pin 49 is then passed through the opening 50 of the flat portion 18 and through a spacing element 51, then through an opening 52 of the ratchet carrying boss 53 or projection 53 into a depression 54 of this

boss. A washer 56 is engaged over the pin 49 and a split key 57 is applied as shown.

It is not necessary that the assembly be made in exactly the way described because, as a matter of fact, the unit including the elements 3, roller 10, and the tubular elements 12 with the frame having the pawl arms 35 are sold as a unit and are applied to the window opening. However, in assembling the opening 41 must be brought in opposition to the slot 15, the pin is then dropped into the opening, and either the element 12 or the pawl or rod 35 is turned through a sufficient angle to prevent disengagement of the pin.

Different positions of the curtain are shown in Figure 2. It will be seen that when in any position except the full line position of this figure, the pull on the curtain 11 is such as to cause the pawls or rods 35 to be urged in the direction of the dotted arrow *b*. In the intermediate position shown in dotted lines in this figure, if it is desired to have the device assume the position shown in full lines, the operator merely pulls in the direction of the dotted arrow *c*, to release the pawls, or if desired the elements 12 may be rotated in direction of the arrow *d* until this element passes the dotted line *e* after which the curtain will act to continue the motion in the same direction to the position shown in full lines in this figure.

It will, of course, be understood that the elements 3 are provided with suitable openings to receive the projections 60 of the curtain 10 so that the spring will act properly.

It will be understood that the provision of the inturned portion 26 to prevent outward movement of the bushing is a feature of the invention.

I claim as my invention:

1. A device of the class described having tubular portions of different diameters one merging into the other, a sleeve fitting within that tubular portion of small diameter and projecting into the tubular portion of larger diameter, a rod slidable in the sleeve and projecting therebeyond, a pin loosely traversing the projecting part of the rod and of less length than the bore of the enlarged tubular portion, and a ratchet element beyond the tubular portion with which the rod is engageable to form a pawl and ratchet combination.

2. A window having a spring-operable curtain roller arranged therein, and having a curtain, a pair of ratchet elements respectively secured at the sides of the window, a tubular element for each ratchet element mounted to swing about the axes of the ratchet elements, each element having tubular portions of different diameters and each having a sleeve secured in that tubular portion of small diameter and projecting into the tubular portion of larger diameter in direction of the ratchet element, a frame connected with the curtain

and having two arms each as a pawl slidable in a respective sleeve, pins loosely traversing respective arms within the enlarged diameter portions of respective tubular elements, each 5 pin engageable with the corresponding sleeve to limit withdrawal of the pawl, the end of the pawls being engageable with the teeth, and the length of each pin being less than the inner diameter of the corresponding enlarged 10 tubular portion.

3. In combination, an element having ratchet teeth, a pivoted arm associated therewith and having a tubular extension having portions of different diameters with that portion 15 of largest diameter nearest the corresponding ratchet element, a bushing held within a portion of smaller diameter and extending into the portion of larger diameter, a rod slidable within the bushing as a pawl 20 and engageable with the teeth of the ratchet element, a pin loosely traversing the rod and arranged to engage the bushing as an abutment after disengagement of the pawl from a tooth, the tubular portion of largest diameter 25 being open at one side to permit the pin to be dropped into operative relation to the pawl, the arrangement being such that after the pawl is rotated to operative position in relation to the ratchet, the walls of the enlarged 30 tubular portion act to prevent disengagement of the pin.

4. An arm rolled from a single piece of metal to provide tubular portions of different diameters one merging into the other, a bushing 35 fitted in the tubular portion of smaller diameter and extending into the other tubular portion beyond the point of mergence, a rod slidable in the bushing and projecting therebeyond into the enlarged tubular portion, a pin loosely traversing the rod and adapted to engage the end of the bushing as 40 a stop, the longitudinal edges of the arm being spaced to provide a longitudinal slot through which the pin can be dropped into operative relation to the rod when the rod is in one position, and to flatten the tubular arm, on that 45 side, the width of the slot being such that after introduction of the pin and turning of the rod to operative position, the wall of the enlarged tubular portion acts to prevent pin disengagement.

5. A rotatably mounted spring curtain roller and curtain thereon, a pair of ratchet elements, an arm for each ratchet element 55 swingingly associated therewith, each comprising a tube having two bore portions of different diameters, a bushing within that bore of small diameter projecting into the bore of large diameter as a stop, a frame connected to the curtain and having extensions 60 as pawls one for each bushing and slidable therein and engageable with the teeth of said ratchet after passage into said large diameter portion beyond the bushing, a pin detachably 65 associated with each pawl as a stop engage-

able with the bushing to limit outward movement thereof in a direction away from the ratchet element, and said tube at the enlarged portion being open at one side to permit the pin to be operatively engaged with the pawl, 70 the arrangement being such that after introduction of the pin and after rotation of one part upon another to bring the pawl in engageable relation to the ratchet, the pin is held by the wall of the enlarged bore portion 75 against accidental disconnection.

In witness whereof, I have hereunto set my hand this 3rd day of July, 1928.
